A. BOYNTON

BAILER BOTTOM

Filed May 8, 1922

UNITED STATES PATENT OFFICE.

ALEXANDER BOYNTON, OF SAN ANTONIO, TEXAS.

BAILER BOTTOM.

Application filed May 8, 1922. Serial No. 559,365.

To all whom it may concern:

Be it known that I, ALEXANDER BOYNTON, a citizen of the United States, and resident of San Antonio, in the county of Bexar and State of Texas, have invented certain new and useful Improvements in Bailer Bottoms, of which the following is a specification.

This invention relates to bailer bottoms especially adapted for use in bailing oil and other wells.

An important object of this invention is to provide a bailer which automatically opens when set down on the derrick sill so as to allow the collected mud and sludge to readily discharge and which also opens when the bailer reaches the bottom so it will receive the mud and sludge to be withdrawn.

A further object is to provide a bailer having its lower end formed with mud and sludge receiving means whereby the downward thrust of the bailer is employed to drive the mud and sludge into the bailer.

A bailer constructed in accordance with this invention is formed with large inlet and outlet means so that the mud and sludge may readily enter the bailer and discharge itself therefrom.

Also a further object is to provide a bailer which is more or less smooth on its exterior so that it will not hang, stick or become locked or pinioned against casing or liner by gravel or slivers going into or coming out of the well.

Also an important object of this invention is to provide a bailer having two rotatably connected valves arranged in superposed relation and having means whereby the wear resulting from the presence of sand grit may be compensated for.

A further object is to provide a bailer which is extremely durable, reliable in use and comparatively cheap to manufacture.

Other objects and advantages of the invention will be apparent during the course of the following description.

In the accompanying drawings forming a part of this application and in which like numerals are employed to designate like parts throughout the same,

Figure 1 is a side elevation of the improved bailer.

Figure 2 is a central vertical sectional view through the same.

Figure 3 is a side elevation of an outer sleeve partly in section.

Figure 4 is a horizontal section on line 4—4 of Figure 2.

In the drawing wherein for the purpose of illustration is shown a preferred embodiment of the invention the numeral 5 designates an inner sleeve which as illustrated in Fig. 2 is substantially longer than the outer sleeve 6 which encircles the lower portion of the inner sleeve.

The outer sleeve 6 is slidably connected to the inner sleeve by means of a transverse pin 8 anchored to the intermediate portion of the sleeve 5 and having its end portions arranged in longitudinally extending slots 9 in the outer sleeve. The sliding connection between the inner and outer sleeves is enclosed by a tubular cover 11 having its forward portion threaded onto the intermediate portion of the outer sleeve as indicated at 12. It will be seen that mud is effectively excluded from the oppositely arranged slots 9 by the cover 11 which, of course, is movable with the outer sleeve.

In carrying out the invention a relatively stationary valve 14 is held within the forward portion of the outer sleeve by a retaining bushing 16, the latter being threaded into the outer sleeve as indicated at 17. The stationary valve 14 is in the nature of a spider and has its upper side firmly in contact with an internal annular shoulder 18 formed on the outer sleeve. The valve 14 is also held against rotation by a set screw 15 threaded thru the outer sleeve. It is thus apparent that the spider or valve 14 is held against movement longitudinally of the outer sleeve and is also held against rotation.

The relatively stationary valve 14 is connected with a similarly constructed valve 20 through the medium of a screw bolt or cap screw 22 and a nut 23 in such manner that the valve 20 may rotate relative to the valve 14. Further the connection between the valves allows wear as a result of the presence of sand and grit to be compensated for without taking the device apart or much labor on the part of the attendant. Attention is also directed to the fact that the connecting members 22, and 23 do not extend beyond the sides of the hubs of the valves and therefore do not in any way interfere with the free passage of mud either

while filling the bailer or discharging mud therefrom. The openings in the upper and lower valves, while somewhat less in area than the cross sectional area of the bailer, are large enough to permit of the rapid filling of the bailer and the discharge of the mud and sludge therefrom.

The upper valve 20 is rigidly connected to an intermediate sleeve 25 arranged between the inner and outer sleeves and having its upper end engaged by an annular shoulder 26 formed on the exterior of the inner sleeve at a point spaced between the ends of the same. With reference to Fig. 15 it will be observed that the exterior of the intermediate sleeve is flush with the exterior of the inner sleeve above the shoulder 26. The lower portion of the inner sleeve is reduced exteriorly to define the annular 20 shoulder 26.

The intermediate sleeve is formed with a pin 27 received within a spiral slot 28 in the inner sleeve and when the valves 14 and 20 are in registration as illustrated in Fig. 2, 25 the pin 27 is in the upper portion of the slot 28. However, when the bailer is extended and the valves are out of registration or closed the pin 27 is received in the lower portion of the slot 28.

30 In operation the improved bailer is lowered into the well and upon encountering mud the inner sleeve will advance with relation to the outer sleeve whereby the valves 14 and 20 will be brought into registration 35 for allowing the mud to enter. It is thus seen that the valves 14 and 20 are brought into registration simultaneously with the engagement of the bailer with the mud so that the weight of the bailer is utilized for forcing the mud into the bailer. When the bailer is filled with mud it is withdrawn and as a rearward pull is exerted on the inner sleeve the intermediate sleeve will be rotated for closing the lower end of the bailer by 40 means of the valves 14 and 20 whereby the escape of mud and sludge is effectively prevented.

When the bailer is completely withdrawn from the well it is set on the bottom of ditch 50 the sill of the derrick and the downward movement of the inner sleeve causes the valves 14 and 20 to again come into registration so that the mud may be effectively discharged. In this operation also the valves 55 are brought into registration simultaneously with the setting of the device on the sill so that the rapid and efficient discharge of the mud and sludge is provided for.

In carrying out the invention the guide 60 pin 8 is positively held in position by the mud excluding cover or tubular member 11 and the pin is made stout enough to prevent shearing. In view of this the accidental disconnection of any of the parts of the bailer 65 while in the well is rendered extremely un-

likely. The pin 8 forms a reliable means for preventing the loss of the outer sleeve and in this respect cooperates with the pin 27 which limits the forward movement of the intermediate sleeve. As illustrated in Fig. 2, 70 the intermediate sleeve is securely connected to the outer sleeve through the medium of the screw bolt 22.

Figure 1 illustrates that the exterior of the bailer is comparatively smooth so that 75 it is not likely to hang or fasten onto any slight projection which might exist in the casing or become wedged or keyed therein by foreign matter.

It is to be understood that the form of the invention herewith shown and described is to be taken merely as a preferred example of the same and that such minor changes in arrangement and construction of parts may be made as will remain within the spirit of 80 the invention and the scope of what is claimed.

Having thus described the invention, what I claim is:—

1. A bailer for wells comprising inner and outer sleeves, means slidably and non-rotatably connecting the sleeves, a relatively stationary valve carried by the outer sleeve, and a second valve cooperating with said first named valve in controlling the supply of 90 mud and sludge to and the discharge of mud and sludge from the bailer.

100 2. A bailer for wells comprising inner and outer sleeves, means slidably and non-rotatably connecting the sleeves, a relatively stationary valve carried by the outer sleeve, a second valve cooperating with said first named valve in controlling the supply of mud and sludge to and the discharge of mud and sludge from the bailer, and an intermediate sleeve arranged between the inner and outer sleeves and having rigid connection with said second named valve.

105 3. A bailer for wells comprising inner and outer sleeves, means slidably and non-rotatably connecting the sleeves, a relatively stationary valve carried by the outer sleeve, a second valve cooperating with said first named valve in controlling the supply of mud to and the discharge of mud from the 110 bailer, an intermediate sleeve arranged between the inner and outer sleeves and having rigid connection with said second named valve, and means rotatably connecting said first and second named valves.

115 120 125 4. A bailer for wells comprising inner and outer sleeves, means slidably and non-rotatably connecting the sleeves, a relatively stationary valve carried by the outer sleeve, a second valve cooperating with said first named valve in controlling the supply of mud to and the discharge of mud from the bailer, an intermediate sleeve arranged between the inner and outer sleeves and having rigid connection with said second named 130

valve, and means rotatably connecting said first and second named valves, there being a pin and spiral slot connection between the inner sleeve and the intermediate sleeve.

5 5. A bailer for wells comprising an inner sleeve, an outer sleeve having slots, a pin extending through the inner sleeve and received in said slots whereby to limit the movement of the outer sleeve with relation 10 to the inner sleeve, a mud excluding tubular member surrounding the outer sleeve and closing said slot and constituting a means to hold the pin in position, an intermediate sleeve arranged between the inner and outer 15 sleeves, coacting valves carried by said intermediate sleeve and said outer sleeve, there being a pin and spiral slot connection between the inner sleeve and the intermediate sleeve for rotating one of the valves when one 20 of the sleeves is moved longitudinally with relation to the other.

6. A bailer for wells comprising an inner sleeve, an outer sleeve having slots, a pin extending through the inner sleeve and received in said slots whereby to limit the movement of the outer sleeve with relation 25 to the inner sleeve, a mud excluding tubular member surrounding the outer sleeve and closing said slots and constituting a means to hold the pin in position, an intermediate sleeve arranged between the inner and outer 30 sleeves, coacting valves carried by said intermediate sleeve and said outer sleeve, there being a pin and spiral slot connection be- 35 tween the inner sleeve and the intermediate sleeve for rotating one of the valves when one of the sleeves is moved longitudinally with relation to the other, and a bushing threaded into the outer sleeve and bearing against 40 one of said valves whereby to hold the same in position.

7. A bailer for wells comprising inner and outer sleeves, the inner sleeve being extended a substantial distance beyond the rear end of the outer sleeve, means slidably connecting 45 the inner and outer sleeves, the forward portion of the inner sleeve being reduced exteriorly whereby to provide an annular shoulder, an intermediate sleeve contacting with said shoulder and surrounding the reduced 50 portion of said inner sleeve, coacting valves carried by the intermediate and outer sleeves, means rotatably connecting said valves and forming a means whereby the same may be adjusted to compensate for 55 wear, a pin carried by one of the sleeves, one of the other sleeves being provided with a spiral slot receiving said pin whereby when one of the sleeves is rotated with relation to the other sleeve when the bailer is set, and 60 a bushing threaded into the forward portion of one of the sleeves and constituting a means to hold one of the valves in position.

8. A bailer comprising a pair of valve members adapted for registration, interfitting sleeves supporting the valve members, and means carried by said sleeves for bringing 65 said valve members into registration.

9. A bailer comprising a pair of valve members adapted for registration, interfitting sleeves supporting said valve members, and means actuated by one sleeve for turning another sleeve and the valve supported thereby whereby the valves are brought 70 into registration.

10. A bailer comprising slidably connected sleeves, a valve carried by one of said sleeves, a second valve adapted for registration with said first named valve, and means actuated by one of said sleeves for bringing said 75 valves into registration.

ALEXANDER BOYNTON
